UNITED STATES PATENT OFFICE

ARTHUR R. SWANSTROM, OF DULUTH, MINNESOTA, ASSIGNOR TO DIAMOND CALK AND HORSESHOE CO., OF DULUTH, MINNESOTA, A CORPORATION OF MINNESOTA

PITCHING HORSESHOE

Application filed February 26, 1931. Serial No. 518,414.

It is an object of the present invention to provide a pitching shoe with hooks at the ends thereof for engaging and holding the stake, the said hooks being formed by cutting away a portion of the material of the sides of the shoe adjacent the ends to reduce the width of said ends and forming projections on said reduced ends cooperating with said cut away portions.

10 It is another object of the invention to provide a pitching shoe with improved calks for eliminating tumbling when the shoe lands and to promote sliding of the shoe toward the stake.

15 Still another object of the invention is to provide a pitching shoe having the extreme ends thereof angularly disposed so that if the end should strike the stake, there will be a tendency for the shoe to rotate and thus ring 20 the stake.

Inasmuch as pitching horseshoes are required to be of prescribed width at the heel opening and at the sides, hooks for any useful purpose cannot be formed at the heel of 25 the shoe by merely providing projections, as has heretofore been suggested because such projections would necessarily be too short. My invention overcomes this difficulty by cutting away a portion of the material of the 30 side members of the shoe to materially reduce the width of the heel ends and providing projections on the reduced ends of said side members which cooperate with the cut away portions to form pronounced hooks 35 which will engage the stake and hold the shoe in place when it lands.

As heretofore constructed, pitching shoes have been provided with calks arranged transversely of the heel ends, as is customary with ordinary horseshoes. Such calks 40 tend to arrest movement of the shoe when it lands and to cause undesirable tumbling of the shoe. By my invention, pitching shoes are provided with longitudinally extending calks 45 which will not impede the progress of the shoe after it lands but which will permit sliding of the shoe into engagement with the stake.

As a further advantage of my invention, I 50 have cut away the extreme ends of the side

members to form angular surfaces which, should they come into contact with the stake, will cause the shoe to rotate instead of causing the shoe to rebound from the stake as is the case when the ends are cut off to form 55 straight lines.

In the accompanying drawings I have illustrated a practical embodiment of my invention. However, I wish it to be understood that I do not limit myself to the exact 60 details of construction or proportion of the parts as shown in these drawings but that the invention may be embodied in other practical forms without departing from the spirit of the invention or the scope thereof as defined in the appended claims.

In these drawings, Fig. 1 is a plan view of a pitching shoe constructed in accordance with my invention and showing the action of the shoe in engaging 70 the stake.

Fig. 2 is a sectional view taken on line 2—2 of Fig. 1; and

Fig. 3 is a bottom plan view of my pitching shoe showing the construction and arrangement of the calks.

In these drawings, I have shown a pitching shoe which conforms to regulations governing size and proportions and which includes a toe portion 10 and side members 11 which terminate a prescribed distance apart 75 to form the so-called heel opening.

Adjacent to the ends of said side members, I have cut away a portion of the material, as at 12, and upon the ends of said side members I have provided projections 13 which 80 cooperate with said cut away portions 12 to form pronounced hooks. It will be noted from an inspection of the drawings that the projections 13 have curved inner edges which 85 complete the curve of the cut out portions 12. Moreover, the extreme outer ends of the side members and of the projections 13 are angularly disposed as at 14. This angular formation of the extreme outer ends of the shoe 90 will be found helpful in the event that the end of the shoe should strike the stake. Instead of the shoe sharply rebounding from the stake, it will be given a rotative movement 95 about the said stake as a center.

Upon the ends of the said side members 11 adjacent the hooks I have provided calks 15 the shape of which is clearly shown in the drawings. It will be seen that the calks have 5 relatively abrupt outer surfaces terminating at the outer edges of said side members 11 whereas the inner surfaces of said calks are of more gradual slope and terminate adjacent the said hooks. By this arrangement, 10 the highest point of said calks will be located nearer to the outer edges of said side members, thus providing surer support for the shoe.

I have also shown my pitching shoe to be 15 provided with a cut out portion 16 on the inner edge of the toe of the shoe. This cut out will also be helpful to engage the stake and hold the shoe in place.

On the toe portion, I have provided a calk 20 17, which as shown in Fig. 3, extends longitudinally of the toe. This calk is of substantially the same construction as the heel calk 15 and has a gradual sloping surface which terminates at the cut out 16. If desired, the calks 17 may be made to extend 25 transversely of the toe, that is to say, in a direction parallel to the calks 15. However, when the calks 15 are provided as shown in Fig. 3, it may be best to have the toe calk extend 30 as in the said figure to form a stop against continued movement of the shoe after it lands.

In Fig. 1, I have shown in dotted lines the 35 position of the shoe just as it has landed adjacent to the stake. Normally, the shoe will rotate in the direction of the arrows in said figure and in so doing the hooks will engage the stake 18, as shown in full lines.

It is believed that the foregoing description 40 will make my invention clear to those skilled in the art and that the numerous advantages of the improvements I have provided will be fully appreciated. Thus, by merely reducing the width of the heel ends 45 of the shoe, I am enabled to provide projections on the said ends which will form pronounced hooks with the inner edges of the side members.

I claim as my invention:

50 1. A pitching horseshoe having side members terminating in spaced ends forming a heel opening, said side members having portions of reduced width adjacent said ends, and projections on said ends cooperating 55 with said portions of reduced width to form pronounced hooks.

2. A pitching horseshoe having side members terminating in spaced ends forming a heel opening, and calks on said ends extending longitudinally of said side members, said calks having abrupt outer surfaces and gradually sloping inner surfaces.

In witness whereof I have hereunto set my hand this 21st day of February, 1931.

ARTHUR R. SWANSTROM.
